UNITED STATES PATENT OFFICE.

EDWARD WILSON, OF ST. LOUIS, MISSOURI, ASSIGNOR TO WILSON ENGINEERING COMPANY, OF ST. LOUIS, MISSOURI, A CORPORATION OF MISSOURI.

COMPRESSOR.

Application filed March 12, 1923. Serial No. 624,588.

To all whom it may concern:

Be it known that I, EDWARD WILSON, a citizen of the United States, residing at St. Louis, Missouri, have invented a new and useful Compressor, of which the following is a specification.

This invention relates to compressors.

An object of the invention is to provide a compressor of the rocking piston type embodying a novel relationship of parts for maintaining the machine uniformly and continuously in a condition of high efficiency and controlling the admission and discharge of air.

Another object of the invention is to provide an efficient oil return device for returning to the machine the oil that has been separated from the compressed air or gas.

Another object of the invention is to provide a compressor of a highly improved construction, with means for automatically maintaining proper adjustment of the operating mechanism.

Another object of the invention is to provide improved means for sealing the bearing of the operating shaft of the compression mechanism to prevent leakage through the bearing.

Other objects will appear from the following description, reference being made to the drawings in which

Fig. 1 is a longitudinal sectional view of my improved compressor.

Fig. 2 is an enlarged view with parts in section of the compression cylinder and rocking pistons, and showing also the valves controlling the discharge of the compression from the cylinder.

Fig. 3 is a cross sectional view on the line 3—3 of Fig. 1, showing the connection for rocking the pistons.

Fig. 4 is a cross sectional view on the line 4—4 of Fig. 1, showing the oil pump device for returning oil to the machine.

Fig. 5 (sheet 1) is an enlarged sectional view of the packing devices in loose relationship before being thrust together.

The shaft 1 of the motor 2 is coupled with the rotary shaft 3 of the compressor by a releasable coupling 4. The shaft 3

has a crank 5 which is connected by a link 6 with a crank 7 on the end of the rotor shaft 8 which is the shaft on which the rocking or oscillating pistons are located. A fly wheel 9 is in connection with the crank 5. The shaft 3 is journaled in a split tapered bushing 10 of bronze or other material and is lubricated by oil contained in the crank member 11 into which the fly wheel 9 dips. The oil is thereby splashed over the walls of the crank chamber and passes through an oil hole 12 opening into the slot in the bushing 10 and is drained back into the crank chamber through a passage 13. The connection from the crank 5 to the shaft 8 is lubricated in the same way.

The operating mechanism of the compressor is mounted in a housing 14. The outer end of the shaft 8 is mounted in a piston 15 while the cranked end of the shaft is mounted in a bushing 16 supported in the wall 17 that separates the crank chamber 11 from the remaining portion of the housing. The crank 7 and bushing 16 may be formed integral as shown. The bushing 16 is on a squared portion of the shaft and is thereby rocked with the shaft, while the piston 15 is made to rock with the shaft by the pins 26 as presently explained.

The stator cylinder 18 is mounted in a rigid support 19 and is held from rotation by keys 20 and is permitted to slide freely in the direction of the axis of the rotor having free axial floating movement. The cylinder 18 is formed with two diametrically opposite sectors 21 on the inside, each being fitted with a radially movable packing shoe 22 extending throughout its length. The shaft 8 extends axially through the cylinder 18 and is provided with two piston sectors 23, each of which is equipped with a radially movable longitudinal packing piece 24 pressing against the inner surfaces of the piston chambers in the cylinder 18 in which chambers the pistons 23 rock or oscillate as the shaft 8 is rocked or oscillated. The packing pieces are lubricated through ports 24^a (Fig. 1) and 24^b (Fig. 2). The piston 15 is formed with a cylinder

head 25 which is made to rock with the pistons 23 by connecting pins 26. The cylinder head 27 at the opposite end is made to rock with the pistons by connecting pins 28. The whole cylinder element is submerged in oil contained in the housing 14. The cylinder head 27 has a cylindrical extension 29 enclosing and forming a housing for a metallic seal, comprising two abutting rings 30 having their opposite faces concave for cooperation with the adjacent convexed end of the supporting bearing 31, which constitutes a differential piston as hereinafter explained, and the convex surface of a ring 32, respectively.

It will be seen that the cylinder end wall 25 is held against the end of the rotor 23 by a nut 15^a and that the cylinder end wall 27 is clamped against the rotor by the construction comprising the nut 16^a, the bushing 16 and the ring 32. Accordingly the nuts 15^a and 16^a constitute clamping elements for holding together the interposed parts. The two rings 30 are mounted on a reduced portion of the bushing 16 with radial clearance to permit sidewise adjusting movement, while the ring 32 is pressed tight on the shaft 8. This seal which is used in place of a stuffing box is self-aligning in all positions and compensates for any misalignment of the rotor bearings so that the full bearing area of the thrust surfaces of the seal are realized at all times. By utilizing the differential pistons 15 and 31 to limit the thrust load upon the wearing surfaces of the seal as hereinafter explained, and obtaining the lapping action of the moving parts submerged in oil, a seal is produced that is automatic in adjustment and which is highly effective in preventing leakage of gas into the crank case.

Gas is drawn into the cylinder through a hollow shaft 8 having a pair of diametrically opposite slots 33 which, during the rocking of said shaft 8, are alternately brought into communication with the two compression chambers in the cylinder 18, passing from one chamber to the other under the packing pieces 22 which act as valves and admit the gas at the end of the stroke in each direction. By this construction I am enabled to dispense with the use of poppet valves and like devices which are subject to certain objections.

Gas is discharged from the compression cylinder 19 through a set of valves, there being two valves for each compression chamber in the cylinder, one valve for each chamber being shown in Fig. 2 and it being understood that there are two other valves of like construction, one for each chamber in the compression cylinder. Each of said valves includes a ring 34 having a valve seat 35 opening into one of the compression chambers, a ring 36 secured within the opening in

the cylinder in which the valve is mounted and having a reduced extension 37 extending into the ring 34 and leaving an annular space between said ring 34 and said extension 37 and having holes 38 forming exits 70 from said annular space, and a valve disc 39 supported for movement between the valve seat 35 and the end of the extension 37. This permits the compressed gas to pass from the compression chambers and prevents 75 the gas from being drawn back into the chambers through said valves, due to the fact that the disc 39 of each valve is moved to closed position on the seat 35 as an incident to the movement of the corresponding 80 piston 23 in a direction away from the valve. The gas passes through the valves described into a groove 40 in the cylinder support 19 and thence through a tube 41, the open upper end of which is above the level of the 85 oil in the housing 14. As the housing 14 contains gas under compression the cylinder is sealed and the rotor bearings are lubricated by oil under this pressure. The seal housing 29 is constructed to limit the quantity of oil forced by gas pressure into the chamber containing the rings 30. The pressure in the chamber containing the rings 30 is relieved by a small port 42 forming a communication from said chamber to the opening in the shaft 8, so that the pressure causing leakage through the seal is always a back pressure or suction pressure to the compression devices. 90

The piston 15 and the extension 31 form differential pistons of which the piston 31 is the larger. These two pistons are acted upon in opposite directions by the pressure within the housing 14 but, owing to the greater area of the piston 31 there is 105 greater pressure upon the seal 30. In practice the areas of the two pistons 15 and 31 are so proportioned that the thrust against the seal does not exceed forty pounds per square inch of the bearing area of the seal 110 when the pressure in the housing 14 is two hundred pounds per square inch, though, of course, this proportion of pressure may be varied without departure from the principle of the invention. 115

In operation air is drawn into the hollow shaft 8 from a receiving chamber 43 having an air inlet 44. A small amount of oil seeps from the seal housing 29 through the bearings into the crank chamber 11. A 120 sump 45 is secured to the under side of the crank chamber 11 and fills with oil free from entrained air. This sump is connected with the suction chamber 43 by a pipe 46, thus providing means for returning the oil to the compressor housing 14. 125

The casting 47 containing the air receiving chamber 43 also contains an oil receiving chamber 48 to which oil is admitted from a pipe 49. The end of the bearing 130

chamber 15 is recessed, said recess containing a pair of blocks 50 actuated against the enclosing wall 51 by a spring 52. These blocks are oscillated with the shaft 8. One 5 of said blocks has an oil receiving chamber 53 (Fig. 4) which receives oil through a port 54 communicating with the chamber 48 and discharges oil through a port 55 communicating with the chamber 43. It is 10 understood that the oil entrained with the compressed gas may be separated by appropriate devices after the gas leaves the housing 14. The separated oil may, of course, be returned to the housing 14 15 through the pipe 49 and the oil measuring and pumping device described.

From the foregoing it will be seen that my invention is a refined mechanism for obtaining all of its intended objects and 20 purposes in a highly efficient manner. Once assembled the parts maintain proper adjustment and accommodate themselves to each other automatically. Since the operating mechanism is thoroughly lubricated the 25 machine does not become overheated and the efficiency is maintained indefinitely.

I am aware that the invention may be modified in numerous particulars without departure from the nature and principle 30 thereof, and I do not restrict myself to any unessential particulars.

What I claim and desire to secure by Letters Patent is:—

1. A compressor, comprising a housing, 35 a support within the housing, a cylinder within the housing, a piston within the cylinder, end walls attached to the piston and closing the ends of the cylinder, and mechanism for rocking the piston and 40 thereby said end walls.
2. A compressor, comprising a non-rotative cylinder, compression chambers within the cylinder, a shaft extending axially through the cylinder, pistons on said shaft 45 extending into said chambers, mechanism for rocking said shaft and thereby said pistons, and end walls closing the ends of said cylinder and arranged to rock with said shaft and pistons.
3. A compressor, comprising a cylinder, 50 compression chambers within the cylinder, a hollow shaft extending axially through the cylinder and having openings arranged to be moved into and out of communication 55 with said compression chambers respectively, valve members supported by the cylinder closing said openings during their movements from one compression chamber to another, pistons on said shaft operating in 60 said compression chambers, end walls for said cylinder arranged to move with said shaft and pistons, and mechanism for rocking said shaft to operate said pistons in said compression chambers.
4. A compressor, comprising a cylinder, 65 compression chambers within the cylinder, a hollow shaft extending axially through the cylinder and having openings arranged to be moved into and out of communication 70 with said compression chambers respectively, valve members supported by the cylinder closing said openings during their movements from one compression chamber to another, pistons on said shaft operating in said compression chambers, end walls for 75 said cylinder arranged to move with said shaft and pistons, mechanism for rocking said shaft to operate said pistons in said compression chambers, and valves supported by said cylinder controlling the discharge of compression from said compression chambers.
5. A compressor, comprising a cylinder, 80 compression chambers within the cylinder, a hollow shaft extending axially through the cylinder and having openings arranged to be moved into and out of communication 85 with said compression chambers respectively, valve members supported by the cylinder closing said openings during their movements from one compression chamber to another, pistons on said shaft operating in said compression chambers, end walls for 90 said cylinder arranged to move with said shaft and pistons, mechanism for rocking said shaft to operate said pistons in said compression chambers, valves supported by said cylinder controlling the discharge of compression from said compression chambers, 95 and means for holding said end walls against the ends of the cylinder.
6. A compressor, comprising a cylinder, 100 a shaft extending axially through the cylinder and having openings for admitting gas into the cylinder, mechanism for rocking said shaft, pistons on said shaft within the cylinder for effecting compression, and means for conducting oil to a point for admission to said cylinder through said shaft.
7. A compressor, comprising a cylinder, 105 a shaft extending axially through the cylinder and having openings for admitting gas into the cylinder, mechanism for rocking said shaft, pistons on said shaft within the cylinder for effecting compression, means for conducting oil to a point for admission to 110 said cylinder through said shaft, and valves supported by the cylinder controlling the discharge of compression therefrom.
8. A compressor, comprising a cylinder, 115 a rock shaft extending axially through the cylinder and having openings for admitting gas and oil into the cylinder, mechanism for rocking said shaft, means for effecting compression in the cylinder as the shaft is 120 rocked, and means for delivering oil to said shaft for admission into said cylinder.
9. A compressor, comprising a cylinder, 125 a rock shaft extending axially through the cylinder and having openings for admitting 130

gas and oil into the cylinder, mechanism for rocking said shaft, means for effecting compression in the cylinder as the shaft is rocked, and means for delivering measured quantities of oil to said shaft for admission into said cylinder with the gas.

10. A compressor, comprising a cylinder, a rock shaft extending axially through the cylinder, a bearing in which said shaft is journalled, compression chambers in said cylinder, pistons on said shaft arranged to operate in said compression chambers to effect compression, valves controlling the discharge of the compressed gas from said chambers, an end wall attached to said pistons, and a series of concave and convex rings preventing leakage through said bearing.

11. A compressor, comprising a cylinder, a housing enclosing said cylinder, a rock shaft extending axially through the cylinder, compression chambers in said cylinder, pistons on said shaft arranged to operate in said compression chambers to effect compression, valves controlling the discharge of the compressed gas from said chambers, an end wall attached to said pistons, a series of concave and convex rings preventing leakage from said housing, and a housing in connection with said end wall enclosing said rings.

12. A compressor, comprising a cylinder, a housing enclosing said cylinder, a rock shaft extending axially through the cylinder, compression chambers in said cylinder, pistons on said shaft arranged to operate in said compression chambers to effect compression, valves controlling the discharge of the compressed gas from said chambers, an end wall attached to said pistons, a series of concave and convex rings preventing leakage from said housing, a housing in connection with said end wall enclosing said rings, and means for admitting gas and oil into said compression chambers through said shaft.

13. A compressor, comprising a cylinder, a housing enclosing said cylinder, compression chambers in said cylinder, a shaft extending axially through said cylinder, means for admitting gas through said shaft into said compression chambers, pistons on said shaft in said compression chambers, end walls attached to said pistons closing the ends of said cylinder, a series of concave and convex rings between one of said walls and the wall of the housing preventing leakage from said housing, a housing on one of said end walls enclosing said rings, and means for conducting oil from said housing into said shaft for admission into said compression chambers.

14. A compressor, comprising a cylinder, a housing enclosing said cylinder, compression chambers in said cylinder, a shaft ex-

tending axially through said cylinder, means for admitting gas through said shaft into said compression chambers, pistons on said shaft in said compression chambers, end walls attached to said pistons closing the ends of said cylinder, a series of concave and convex rings between one of said walls and the wall of the housing preventing leakage from said housing, a housing on one of said end walls enclosing said rings, means for conducting oil from said housing into said shaft for admission into said compression chambers, and means for delivering oil to said shaft from another source for admission into said compression chambers.

15. A compressor, comprising a cylinder, a housing enclosing said cylinder, compression chambers in said cylinder, a shaft extending axially through said cylinder, means for admitting gas through said shaft into said compression chambers, pistons on said shaft in said compression chambers, end walls attached to said pistons closing the ends of said cylinder, a series of concave and convex rings between one of said walls and the wall of the housing preventing leakage from said housing, a housing on one of said end walls enclosing said rings, and valves supported by said cylinder controlling the discharge of compression therefrom.

16. A compressor, comprising a cylinder, a housing for receiving the compressed gas and arranged to contain oil submerging said cylinder and a portion of the following named parts, compression chambers in said cylinder, a shaft extending axially through said cylinder, means for admitting gas through said shaft into said compression chambers, pistons on said shaft in said compression chambers, end walls attached to said pistons closing the ends of said cylinder, a series of concave and convex rings between one of said walls and the wall of the housing preventing leakage from said housing, a housing on one of said end walls enclosing said rings, and valves supported by said cylinder controlling the discharge of compression therefrom to said first-named housing.

17. A compressor, comprising a cylinder, a housing for receiving the compressed gas and arranged to contain oil submerging said cylinder and a portion of the following named parts, compression chambers in said cylinder, a shaft extending axially through said cylinder, means for admitting gas through said shaft into said compression chambers, pistons on said shaft in said compression chambers, end walls attached to said pistons closing the ends of said cylinder, a series of concave and convex rings between one of said walls and the wall of the housing preventing leakage from said housing, a housing on one of said end walls enclosing said rings, and means for conduct-

ing the compressed gas from said cylinder to the upper portion of said first-named housing above the level of the oil.

18. In a compressor, a cylinder, mechanism within the cylinder for effecting compression therein, means for operating said mechanism, an end wall for said cylinder arranged to operate with said mechanism relative to the cylinder, a housing for receiving the compressed gas, and means supported by said mechanism for preventing leakage from said housing.

19. In a compressor, a cylinder, mechanism within the cylinder for effecting compression therein, means for operating said mechanism, an end wall for said cylinder arranged to operate with said mechanism relative to the cylinder, a housing for receiving the compressed gas, means for preventing leakage from said housing, a housing in connection with said end wall enclosing said leakage preventing means, and a communication from said second housing through said mechanism to said cylinder for conducting oil from said second housing into said cylinder.

20. In a compressor, a cylinder, mechanism within the cylinder for effecting compression therein, means for operating said mechanism, an end wall for said cylinder arranged to operate with said mechanism relative to the cylinder, a housing for receiving the compressed gas, means for preventing leakage from said housing, a housing in connection with said end wall enclosing said leakage preventing means, a communication from said second housing through said mechanism to said cylinder for conducting oil from said second housing into said cylinder, and means for conducting oil and gas from another source to said cylinder.

21. A compressor, comprising a housing, a partition dividing said housing into two separate compartments arranged to contain oil, compression mechanism in one of said compartments, mechanism in the other compartment for operating said compression mechanism, and means for conducting oil from said last-named compartment to the compression mechanism.

22. A compressor, comprising compression mechanism, means for operating the compression mechanism, a chamber arranged to receive gas and oil for admission to the compression mechanism, and a device for delivering measured quantities of oil into said chamber.

23. A compressor, comprising compression mechanism, means for operating the compression mechanism, a chamber arranged to receive oil for admission to the compression mechanism, and means controlling the admission of oil into said chamber.

24. In a compressor, compression mech-

anism, means for operating the compression mechanism, and means operated by the compression mechanism for delivering oil thereto.

25. In a compressor, compression mechanism, means for operating the compression mechanism, and means operated by the compression mechanism for delivering oil therefrom to one source and gas from another source.

26. In a compressor, a cylinder, compression chambers in the cylinder, rocking pistons in said chambers, an end wall for said cylinder attached to said pistons, a rigid element having a convex end toward said end wall, a ring having a concave surface abutting against said convex end, a ring abutting against said first-named ring toward said end wall and having a concavity in the side toward the end wall, and a ring having one side abutting against said end wall and having a convex side abutting against the concavity in said second ring.

27. In a compressor, a cylinder, compression chambers in the cylinder, rocking pistons in said chambers, an end wall for said cylinder attached to said pistons, a rigid element having a convex end toward said end wall, a ring having a concave surface abutting against said convex end, a ring abutting against said first-named ring toward said end wall and having a concavity in the side toward the end wall, a ring having one side abutting against said end wall and having a convex side abutting against the concavity in said second ring, and a housing in connection with said end wall enclosing said rings.

28. In a compressor, a cylinder, compression chambers in the cylinder, rocking pistons in said chambers, an end wall for said cylinder attached to said pistons, a rigid element having a convex end toward said end wall, a ring having a concave surface abutting against said convex end, a ring abutting against said first-named ring toward said end wall and having a concavity in the side toward the end wall, a ring having one side abutting against said end wall and having a convex side abutting against the concavity in said second ring, and a housing in connection with said end wall enclosing said rings and having its end opposite from said end wall operating around said rigid element.

29. In a compressor, a cylinder, compression chambers in the cylinder, a rotor in the cylinder for effecting compression, a seal for preventing leakage of gas, and differential pistons for limiting the thrust load upon the seal.

30. In a compressor, a housing, compression mechanism within the housing, means for operating the compression mechanism, a seal for preventing leakage of gas from the

housing, and differential pistons for limiting the thrust load upon the seal when the compression mechanism is in operation.

31. A compressor, comprising a housing, 5 a cylinder within the housing, compression mechanism within the cylinder, means for operating said compression mechanism to effect compression, means for conducting the compressed gas from said cylinder into 10 the housing, a seal for preventing leakage of gas from the housing, and differential pistons operatively related to said compression mechanism for limiting the thrust load upon said seal.

32. A compressor, comprising a housing, a cylinder within the housing, a rotor within the cylinder, mechanism for operating the rotor, end walls against the ends of the rotor, supporting bearings for the rotor, a 20 seal for preventing leakage of gas through said bearings, and differential pistons for limiting the thrust load upon said seal.

33. In a compressor, a housing, compression mechanism within the housing, means 25 for operating the compression mechanism, a seal for preventing leakage of gas from the housing, and differential pistons acted on by the compressed gas in the housing for limiting the thrust load upon the seal 30 when the compression mechanism is in operation.

34. In a compressor, a cylinder, compression chambers in the cylinder, a rotor in the cylinder for effecting compression, a 35 seal for preventing leakage of gas, and differential pistons outside of the cylinder acted upon by the compressed gas to limit the thrust load upon the seal.

35. A compressor, comprising a housing, 40 a cylinder within the housing, compression mechanism within the cylinder, means for operating said compression mechanism to

effect compression, means for conducting the compressed gas from the cylinder into the housing, a seal for preventing leakage 45 of gas from the housing, and differential pistons acted upon by the compressed gas to limit the thrust load upon said seal.

36. A compressor, comprising a housing, a cylinder within the housing, a rotor within the cylinder, mechanism for operating the rotor, end walls against the ends of the rotor, supporting bearings for the rotor, a seal for preventing leakage of gas through 55 said bearings, and differential pistons acted upon by the compressed gas for limiting the thrust load upon said seal.

37. A compressor, comprising a housing, a cylinder within the housing, a rotor within the cylinder, mechanism for operating 60 the rotor to compress gas, means for conducting the compressed gas from the cylinder to the housing, a seal for preventing leakage of gas from the housing, differential pistons, and means for utilizing the pressure in the housing to hold the seal closed 65 tight and to act on the differential pistons to limit the thrust load upon the seal.

38. A compressor, comprising a housing, a cylinder within the housing, a rotor within the cylinder, mechanism for operating the rotor to compress gas, means for conducting the compressed gas from the cylinder to the housing, a seal for preventing leakage of gas from the housing, differential pistons, means for utilizing the pressure in the housing to hold the seal closed 70 tight and to act on the differential pistons to limit the thrust load upon the seal, a cylinder in the housing enclosing the seal, 75 and a passage from said last-named cylinder opening into the first-named cylinder.

EDWARD WILSON.
